UNITED STATES PATENT OFFICE.

CYRUS W. TODD, OF ORWELL, VERMONT.

AX-HELVE GRIP.

SPECIFICATION forming part of Letters Patent No. 693,463, dated February 18, 1902.

Application filed June 12, 1901. Serial No. 64,236. (No model.)

To all whom it may concern:

Be it known that I, CYRUS W. TODD, a citizen of the United States, residing at Orwell, in the county of Addison, State of Vermont, have invented certain new and useful Improvements in Ax-Helve Grips, of which the following is a full description, such as will enable others skilled in the art which it appertains to make and use the same, reference being had to the accompanying drawings.

My invention has relation to ax-helve grips; and it consists in the novel construction and arrangement of its parts, as hereinafter described.

15 The object of my invention is to provide a metallic detachable grip for ax-helves, the grip being hollow throughout its interior, thereby rendering it light in weight, and having at one end a socket with tapering walls 20 adapted to receive the end of the helve, which is tapered to correspond. The socketed end of the grip is provided with an external bead, which is adapted to strengthen that portion of the grip where the greatest strain comes. 25 The other end of the grip is provided with a surface at right angles to the longitudinal axis of the grip, and the center of this surface is substantially alined with the longitudinal axis of the helve. This surface is intended to receive the blow when the grip is 30 driven in place on the helve, and being located as described the force is sent direct along the grip, and a very tight joint between the grip and the helve can be made.

35 A further object of the invention is to provide a grip that can be removed from one helve and placed upon another and one that can be turned slightly to one side or the other to suit the fancy of the axman.

40 In the accompanying drawings, Figure 1 is a longitudinal sectional view of the grip and a portion of the helve. Fig. 2 is an end view of the grip, showing the transverse longitudinal axis of the same alined with that of the 45 ax-head. Fig. 3 is an end view of the grip, showing the same turned to one side with relation to the ax-head; and Fig. 4 is an end view of the grip, showing the same turned to the opposite side with relation to the ax- 50 head.

The grip 1 is hollow throughout its interior, and its general contour is substantially the

same as that of an ax-handle end, with the exception that it is provided at one end with an external strengthening-bead 2 and at the opposite end with a surface 3, the object of which will be hereinafter explained. 55

The grip is made of any suitable material, such as iron, steel, or aluminium. At its inner end it is provided with the socket 4, having inclined walls, said socket being adapted to receive the end of the ax-helve 5. A screw 6 extends transversely through the helve in a manner as shown in Fig. 1 and securely holds the grip to the helve, the bead 60 2 strengthening the grip at the point where the greatest strain comes during the use of the ax. The surface 3 is adapted to receive the force of the blow in driving the grip on the helve. The center of the said surface is 65 substantially alined with the longitudinal axis of the helve, so that the force is sent direct and the grip is forced squarely in place without binding.

As shown in Figs. 3 and 4, the grip may be 70 turned slightly to one side or the other with relation to the longitudinal axis of the ax-head to suit the fancy of the axman or it may be placed in a position as shown in Fig. 2.

The advantages of my invention are as follows and appeal most to choppers who are operating in isolated sections: The most prolific cause of trouble and loss of time in such sections is the breaking of ax-helves. When this happens, it is necessary to send long distances for new ones, and when they arrive they are usually crooked, made of poor timber, and of different pattern. It always takes the best part of a day for a chopper to get used to a new helve. A broken helve means 80 a lost hand from the gang and a lost day's wages for himself. With my invention when a chopper breaks his helve in the woods he can cut down a stick large enough to fill the ax-eye, flat it, hew it a little, fit the grip on 85 with his jackknife, and finish his day's work, the fitting of the new stick requiring about twenty minutes' time. He can shape the stick when he gets time, and it is always the same old grip that he is used to. He can put the 90 grip on to suit himself—straight with the ax-head or turned a little to one side or the other.

The chopper can at will detach the grip

from the helve, which renders the ax much less liable to misappropriation.

By providing the socket 4 with tapering walls a green stick may be used for the helve, and when it shrinks the screw 6 can be removed and the grip can be driven on farther, the surface 3 receiving the blow and thus saving the end of the grip from being battered.

Having described my invention, what I claim as new, and desire to secure by Letters Patent, is—

1. In combination with an ax-helve made of a straight piece, a detachable grip constituting an extension of the helve for a greater part of the gripping portion thereof, said grip consisting of a single piece of integral portions, said grip in itself forming a complete handhold, said grip being curved down along its longitudinal upper and lower edges and merging at its end into a circumferentially-flared butt, and a means for securing the grip to the helve.

2. In combination with an ax-helve made of a straight piece, a detachable grip constituting an extension of the helve for a greater part of the gripping portion thereof, said grip consisting of a single piece of integral portions, said grip forming in itself a complete handhold, said grip being curved down along its longitudinal upper and lower edges and merging at its end into a circumferentially-flared butt, said grip having at its outer end a plane surface the middle of which is substantially alined with the central longitudinal axis of the helve, said plane surface extending at right angles to said axis and a means for securing the grip to the helve.

In testimony whereof I have signed my name to this specification in the presence of two witnesses.

CYRUS W. TODD.
